UNITED STATES PATENT OFFICE

MARY HALLOCK GREENEWAHL, OF PHILADELPHIA, PENNSYLVANIA

MOTOR-ACTUATED SWITCH

Original application filed April 26, 1924, Serial No. 709,283. Patent No. 1,793,284, dated February 17, 1931.
 Divided and this application filed January 7, 1927. Serial No. 159,609.

My invention relates to means for controlling electric energy and particularly to motor operated mechanisms therefor. This is a division of my application Serial 709,283, filed 5 April 26, 1924, now Patent Number 1,793,284 on Feb. 17, 1931.

One object of my invention is to provide a current modifying mechanism comprising a plurality of plural contact, fluid connector 10 switches and means for actuating the same serially, said actuating means being under the volitional manual control of an operator.

Another object of my invention is to provide a current controlling mechanism having 15 means for limiting the operation of the actuating means in either direction of operation.

Another object of my invention is to provide a relatively simple and compact current controlling mechanism of the fluid connector 20 type that shall be manually or motor operated and permit of controlling relatively large amounts of electric energy by a relatively small number of switches, clean, beautiful in appearance so that concealing it is not necessary if not desired, and carrying within itself 25 the safety element that when a switch is broken through overloading it constitutes a safety fuse.

A further object of my invention is to provide an object with configuration, one such 30 object varying from another, that can automatically carry out any variousness of sequence in degree energy translation after such has been found useful by a previous 35 choice or need volitionally arrived at by manual control of said energy.

A further object of my invention is to provide means for connecting up such a mechanically actuating configuration to a regular motive force such as a motor or motor driven 40 energy.

In practicing my invention I provide a plurality of tubes of electric-insulating material, each having a plurality of terminal members 45 extending into the same and containing a quantity of electric conducting fluid, that are pivotally mounted on a suitable frame. A shaft, having a plurality of spaced portions thereon is rotatably mounted in the frame 50 and actuated by an electric motor that is

under the volitional control of an operator or its automatic counterpart. Means are provided for giving each of the tubes a turning movement. They are also severally provided with means for initiating the engagement of the successive tubes and with means for being held in their limiting positions. The switch actuating means is provided with means for de-energizing the motor to limit the operation thereof in either direction, and 60 with means for automatically de-energizing the motor when certain effects are in automatic play.

In a modified form of device embodying my invention I provide a plurality of tubes of substantially annular shape, each having a plurality of spaced contact members extending into the same and partially filled with a suitable electric conducting fluid. Each annular tube is secured on a suitable 70 mounting means, which has operatively associated therewith a gear wheel having only a partial set of teeth. All of the annular tubes are loosely mounted in spaced relation on a suitable supporting shaft. A motor driven shaft extends parallel to and spaced from the supporting shaft and has mounted thereon a plurality of pinions that are adapted to mesh with and actuate the annular tubes serially.

In all forms of device embodying my invention the first plural contact fluid connector tube is not permitted to become operatively disconnected from the driving means.

I provide a motive power for actuating the switch mechanism that is preferably an electric motor under the volitional manual control of an operator as to speed and direction of operation. I also provide an automatically operating motive power control means comprising a member of cam shape that is actuated by the switch mechanism and that is effective to vary the speed of the motive power in any predetermined sequence.

In the drawings,

Fig. 10 is a top plan view of a modified form of device embodying my invention, and,

Fig. 11 is a view, in end elevation thereof.

Referring more particularly to Figs. 1 to 3 of the drawings, I provide a vertically extending shaft 21, the lower end of which is located in a suitable step bearing 22 which is, in turn, secured to a base member 23 of a skeleton framework 24. The step bearing 22 is secured to the member 23 by a plurality of machine bolts 25. The shaft 21 is provided with a plurality of screw threaded sections 26, 27, and 28, the screw threads whereof are relatively deep and are preferably square. The hereinbefore mentioned screw threaded portions or sections are separated by portions of the shaft 21 having no screw threads thereon and designated by the numerals 29 and 31 respectively.

The frame 24 comprises the hereinbefore mentioned bottom member 23, a vertically extending side member 32 and a plurality of horizontally extending portions numbered respectively 33, 34, 35 and 36. The free end of the member 33 is provided with a removable cap member 37 and has an opening therethrough to receive the upper plain end 38 of the shaft 21 and permit rotation thereof.

The member 34 is provided with a substantially similar cap 39, while the members 35 and 36 have cap members 41 and 42 associated therewith. All of the cap members are bolted against the outer end portions of the respective members by a plurality of bolts 43. While the cap member 37 cooperates with the outer end of the member 33 to constitute a bearing for the upper end of the shaft, the other cap members do not necessarily constitute bearing members and the openings therethrough may be slightly larger than the external diameter of the shaft.

A worm gear 44 is secured to the lower end of the shaft 21 immediately above the step bearing and is operatively engaged by a worm 45 that is mounted on the outer end

of the shaft of an electric motor 46 which is, in turn, bolted to the upper surface of the member 23.

The members 33, 34, 35, and 36 are spaced a suitable distance apart to permit of mounting between respective pairs of these members a plural contact, fluid connector switch comprising an elongated tube 47 of a suitable electric-insulating material, such as glass or quartz. The tube 47 is mounted against one side of a bar 48 of a suitable electric-insulating material such as asbestos lumber or bakelite. Suitable clamping straps 49 and 51 may be employed to hold the tube 47 against its supporting plate 48. The tube 47 has a plurality of contact terminals 52, 53, 54, 55, and 56 extending into the same, the outer ends thereof being connected to suitable contact terminals that are mounted on the plate 48 immediately above the tube 47 substantially as illustrated in Fig. 1 of the drawings. A quantity 57, of a suitable conducting fluid such as mercury, is placed within the tube which may either be evacuated, or may be filled with a suitable gas or gases that are adapted to prevent as far as possible, the formation of sparks or arcs during the operation of the switch or surface oxidization of the conducting fluid.

A plurality of flexible conductors may be employed to connect the terminals on the bar 48 to fixed contact terminals mounted on a plate of electric-insulating material (not shown) that is, in turn, secured against the skeleton framework, or if desired, a supply circuit conductor and a plurality of conductors connecting the terminals on the bar 48 to the light sources to be controlled, may be employed. As either of these constructions may be employed in accordance to the particular conditions and as such details are well known in the art, I have not illustrated them in detail.

The plate 48 is pivotally mounted, at its rear end, by means of a suitable hinge member 58 on the member 34 adjacent to the vertically extending member 32. A spring member 59 that has one end connected to the member 33 and its other end connected to the top of the plate 48 yieldingly holds the plate and switch in their upwardly tilted position wherein the upper and forward corner of the plate 48 operatively engages the under surface of the member 33. A lug 61 is secured to the lower end of a spring member 62, the upper end of which is suitably secured against a projecting upward shoulder at the front end of the plate 48, a spring 63 being provided at the lower end of the member 62 to press the lug 61 outwardly from the plate 48.

Means for holding the switch member in its fully operative position comprises a resilient member 64, of substantially U-shape, that is secured to the upper surface of the

member 34 where it may be engaged by a suitably shaped lug 65 that is mounted on the rear surface of the plate 48.

A substantially similar switch member 5 comprising a tube 47a and a plate 48a is pivotally mounted on the upper surface of the member 35 and a third switch member comprising a tube 47b and a plate 48b is similarly mounted, on the upper surface of the member 36. As all of the switch members and other appurtenances hereinbefore described in connection with the uppermost switch are the same, I have not thought it necessary to describe or number the respective switches 10 in detail and have also illustrated them in different positions. Whereas the uppermost switch is shown in its fully operative position, the intermediate switch member is shown in its intermediate position, while the 15 lowermost switch is illustrated as in its normal inoperative position.

Means are provided on all switch members except the lowermost one for initiating the actuation of a successive switch and this 20 means comprises a lug 66 that is suitably secured against the lower edge or face of the plate 48 and that is adapted to extend through an opening 67 in the supporting member substantially as illustrated in the upper part 25 of Fig. 1.

Suitable means (not shown) may be provided to serve as guide members for the forward end of the switch supporting bars 48, 48a and 48b in their turning movement to 30 prevent any movement laterally thereof as a result of the friction between the screw threads and the lugs 61.

While I have illustrated a switch mechanism comprising three plural contact fluid 35 connector switches, I do not wish to be limited to this particular number as any suitable number of such switches may be employed and be operated serially or successively in a manner to be hereinafter set forth 40 in detail. While I have illustrated a switch provided with five terminal contact members, I may employ any number of such contact terminals as may be found possible to embody or associate with such a switch, or as 45 50 may be found desirable.

The upper end of the shaft 21 projecting through the upper bearing hereinbefore described is reduced in diameter as indicated by the numeral 68 and has mounted thereon 55 a suitable pinion 69. The pinion 69 meshes with a gear wheel 71 that is mounted on a short shaft 72 that is rotatably mounted in the upper surface of the member 33. A pinion 73 is mounted on the shaft 72 and meshes 60 with a gear wheel 74 that is loosely mounted on a short shaft 75 mounted on and supported by the member 33. A dial 76 is secured on the upper end of the shaft 75 and has a suitable scale marked thereon. This scale is 65 indicated generally only by the numeral 77 in

Fig. 2 of the drawings and is preferably marked with the number of light sources to indicate by the turning movement of the gear wheel 74, and more particularly by the position of a pointer 78 provided thereon, the 70 number of light sources energized at any time during the operation of the switch mechanism.

Means for limiting the turning movement of the shaft 21 in either direction of operation comprise two limit switches 79 and 81 that are supported on the upper surface of the member 33. Each of the limit switches comprises a fixed contact terminal 82 and a movable contact that is carried by a spring arm 83, both the fixed contact terminal and the movable contact terminal being suitably insulated from the metal member 33. The two limit switches are located in oppositely spaced positions relatively to each other and are adapted to be engaged by a pin 84 that extends through the gear wheel 74 at both sides thereof, one of the limit switches being located above the upper face of the gear wheel 74, while the other limit switch is located below the gear wheel.

In Fig. 6 of the drawings I have illustrated a diagram of connections for the motor 46, which is here shown as a shunt wound direct current motor in order to more clearly 95 describe its control, although of course any suitable or desired type of motor may be employed. Suitable supply circuit conductors 85 and 86 are connected to the fixed terminals of a two-pole double throw switch 87. A 100 fixed terminal member 88 at the right hand side of the switch 87 is connected to one terminal of the armature of the motor 46 through one of the limit switches, for example limit switch 79. A second terminal 89 is 105 connected to a pivotally mounted lever 91 that is secured against the under surface of a table top 92, a spring member 93 being provided to yieldingly hold the lever 91 in its inoperative position. An actuating button 94 is secured to the free end of the lever 91 and extends through the top 92 to permit an operator to effect a turning movement of the lever 91, whereby part or all of a resistor member 95 may be cut out of the circuit of 110 the armature of the motor 46. The second limit switch 81 is connected between the contact terminal 89 and a diagonally opposite stationary contact terminal 96. A second stationary contact terminal 97 is located at the 115 left hand side of the switch and is electrically connected to the same terminal of the motor armature as is the switch terminal 88.

The general construction of the switch and of the electrical connections of the same with the manually controlled resistor 95 is such that the motor will rotate in a predetermined direction when the contact bridging members of the switch 87 operatively engage the terminals 88 and 89 respectively. The speed 120 125 130

of rotation of the motor is determined by the amount of resistance cut out of the circuit of the armature of the motor, and the duration of its operation is determined by the length of time during which the operator depresses the lever 91. When the contact bridging members of the switch 87 are moved in the opposite direction so that the contact terminals 96 and 97 are engaged, the motor 10 runs in the opposite direction at a speed that is in accordance with the amount which the lever 91 is depressed.

While I have illustrated, in Fig. 1 of the drawings, a single set of switches, I may employ plural sets of switches and I have illustrated two such switches actuated substantially simultaneously in Fig. 8 of the drawings. I have there illustrated a double frame, the left hand frame being substantially the same as the right hand frame and comprising a vertically-extending side member 98, a horizontally extending upper member 99 and a lower member 101. The inner ends of the respective members 34, 35, 99, 23 and 101 are enlarged in substantially the same manner as is shown for the member 33 in Fig. 2 of the drawings, and these ends are held together in proper operative position by a plurality of machine bolts 30 102. A second switch member 103, comprising a tubular member 47 and a supporting plate 48, is mounted in opposed relation to the first switch member located at the right hand side of the shaft 21. As the construction and operation of the switch member 103 is substantially the same as for those hereinbefore described, it is not deemed necessary to further describe it in detail. The left hand frame is substantially a duplicate 40 of the right hand frame hereinbefore described and more particularly illustrated in Fig. 1 of the drawings. While I have shown only a portion of the switch mechanism in Fig. 8, the construction of the entire device 45 will be evident therefrom.

While I have illustrated, in Fig. 8 of the drawings, two switches between the pairs of horizontally extending members, any suitable or desired number of such switches may 50 be employed. For instance, by providing three skeleton frames spaced equi-distantly in a horizontal plane around the shaft 21, I am enabled to mount three such switches instead of two as illustrated in Fig. 8 of the drawings. Similarly by providing four skeleton frames equi-distantly spaced I may 55 mount four such switches and actuate them substantially simultaneously. This construction permits of increasing the capacity 60 of the switch mechanism by the simple expedient of increasing the number of fluid connector switches that are actuated substantially simultaneously. One motor may actuate a plurality of such switch mechanisms 65 whereby the illumination of all parts of an

auditorium may be simultaneously controlled.

In Figs. 10 and 11 of the drawings I have illustrated a modified form of device embodying my invention, in which I employ fluid connector tubes of substantially annular form instead of the elongated form hereinbefore described. A base plate 104 has mounted thereon a pair of spaced bearing members 105 and 106 that support a shaft member 107. The shaft member 107 has 70 mounted thereon a plurality of annular tubes 108, 109, and 111 that are substantially identical in construction. Each of the tubes 108, 109, and 111 comprises an annulus of a suitable electric-insulating material, such as 80 quartz or glass, that has a plurality of spaced contact terminals 112 extending into the tube through the outer peripheral surface thereof. As all of the terminal members are of the same construction I have designated them by 85 the same number. I have illustrated eight such terminal members spaced substantially equidistantly from each other and extending over slightly more than ninety degrees of the periphery. A quantity 113 of a suitable 90 conducting fluid, such as mercury, is located within the respective annular tubes and is just sufficient to fill substantially one half the interior of the tube.

Each of the annular tubes is clamped between two cooperating plates 114 and 115 that are each of substantially circular shape, and are held together by a plurality of machine screws 116. The respective plates 114 and 115 are provided with a groove in their 100 opposing outer edges that is of such diameter as to receive the annular tube lined with a protecting material and to hold it tightly between the two plates. The annular tubes, together with the supporting plates, are loosely mounted on the shaft 107 and are held in spaced relation by pairs of collars 117 and 118 that are secured on the shaft in any suitable manner. The annular tubes are therefore free to turn on the shaft but are 110 prevented from longitudinal movement relatively thereto.

The annular tube 108 has a gear wheel 119 operatively associated therewith by being suitably secured against the outer surface of 115 the plate 115, while the tube 109 has a gear wheel 121 operatively associated therewith, and the tube 111 has a gear wheel 122 associated therewith. The tubes therefore turn with the respective gear wheels.

A second shaft 123 is supported in a plurality of bearing members 124 and 125 on the base 104 and is aligned substantially parallel to the shaft 107. A worm gear wheel 126 is mounted on the shaft 123 adjacent to one end 120 thereof, and is operatively engaged by a worm 127 that is mounted on the outer end of the shaft of a suitable driving motor 128 which is, in turn, mounted on a supporting base 129 125 located on the base plate 104 in order that it 130

may be located properly relatively to the worm gear wheel 126. Collars 131 are secured to the shaft 123 outside of the bearing members 124 and 125 to prevent any longitudinal movement of the shaft in its bearings. A plurality of pinions 132, 133, and 134 are secured to the shaft 123 and are so located that under the proper conditions of operation they may mesh with the gear wheels 119, 121 and 122 respectively. Each of the hereinbefore described gear wheels is provided with teeth over a portion only of its periphery, for a purpose to be hereinafter described in detail.

15 The flexible lead wires from the respective contact terminals of the tubes 108, 109, and 111 extend to stationary contact terminals mounted on terminal boards 135, 136, and 137 respectively, the contact terminals mounted thereon being so constructed as to permit of conductors indicated by the numeral 138 to be connected thereto.

20 A limit switch 139 is provided in such location as to be operated by a member 141 that is mounted on the plate 114 associated with the annular tube 108 and is effective to open the energizing circuit of the motor 128 when the tube 108 has been given a turning movement in a clockwise direction as viewed from the right hand end of the shaft 107, and it is desired to terminate the turning movement thereof. A similar limit switch 142 is mounted on the bearing member 105 and is actuated by a pin 143 that is carried by the gear wheel 122. The limit switch 142 is effective to limit the operation of the motor in causing a turning movement of the gear wheel 122 in a counter clockwise direction as viewed from the right hand end of the shaft 107.

25 In actual operation the turning movement of the gear wheel 119 and therefore of the tube 108 is terminated while the pinion 132 is still in mesh with the teeth of the gear wheel 119. The turning movement of the gear wheel 122 in a counter clockwise direction is terminated while the teeth thereof are still in mesh with the pinion 134. Means for initiating the operation of the gear wheel 121 are constituted by a pin 144 mounted on the gear wheel 119 and effective to operatively engage a pin 145 carried by the gear wheel 121. Means for initiating the operation of the gear wheel 122 is constituted by a pin 146 carried by the gear wheel 121 and effective 30 to engage a pin 147 carried by the gear wheel 122. The terminal boards 136 and 137 carry resilient members 148 and 149 respectively which normally engage the pins 145 and 147 respectively and yieldingly hold the gear wheels 121 and 122 in their normal inoperative positions wherein no circuit is energized through the respective fluid connector switch tubes 109 and 111 and which also hold the gear wheels 119 and 121 respectively in their fully energized or operative positions.

35 Referring more particularly to the mechanism illustrated in Fig. 1 of the drawings, the respective plural contact fluid connector switches are illustrated in three different positions; the uppermost switch is shown in its 70 fully energized position, the second switch is shown in its partially energized position, and the lowermost switch is shown in its fully de-energized or inoperative position. In the operation of the mechanism it is necessary that 75 the member 61 of the uppermost switch be always in engagement with the screw threads of the portion 26, and the limit switch 79 is so arranged in relation to the pin 84 that such engagement at the upper limit of travel of 80 the uppermost switch 47 is maintained. In other words, the turning movement of the uppermost switch in a clockwise direction is continued only enough to interrupt the circuits that are established thereby and there- 85 through without the member 61 being disengaged from the screw threaded portion 26. This is for the reason that when the shaft 21 is actuated in such direction as to cause a turning movement of the uppermost switch 90 in a counter clockwise direction on its pivotal support, no means is provided to effect operative engagement of the lug 61 with the screw threads of the portion 26 and hence the lug 61 must remain in engagement with 95 the screw threaded portion.

40 If it be assumed that the switch 87 illustrated in Fig. 6 of the drawings be tilted to the right to engage the terminals 88 and 89 to effect a turning movement of the tube 100 47 of the uppermost switch in a clockwise direction, the pin 84 will finally engage the limit switch 79 and actuate the same to de-energize the motor, thereby preventing fur- 105 ther rotation of the driving shaft 21. By 105 moving the reversing switch 87 to its second operative position wherein the terminals 96 and 97 are engaged, the motor is energized to run in the opposite direction and the limit switch 79 is then immediately permitted to 110 reclose. When the motor 46 is energized to actuate the shaft 21 and to effect a turning movement of the switches in a counter-clock- 115 wise direction and the uppermost switch has reached a position that is somewhat lower than that illustrated by the intermediate switch in Fig. 1 of the drawings, the lug 66 secured to the supporting plate 48 engages the top of the second or successive switch bar 48a and pushes it downwardly until the member 61 operatively engages the screw- 120 threaded portion 27. The turning movement of the uppermost switch continues until the member 61 thereof occupies substantially the 125 position illustrated in Fig. 1 of the drawings when the lug 65 operatively engages the re- 130 sistant holding means 64, and the uppermost switch is held in substantially the position shown in the drawings. The intermediate switch is given a turning movement on its

hinge by the continued actuation of the shaft 21 and when the lug 66 carried by it operatively engages the upper edge of the supporting bar 48b, the latter is given a preliminary 5 turning movement in a counter clockwise direction until the lug 61 carried thereby engages the screw threaded portion 28. Further actuation of the shaft 21 causes a turning movement of the intermediate switch 10 until it is yieldingly held in its limiting and substantially horizontal position.

The turning movement of the lowest switch is continued until it is in almost horizontal position with the member 61 still fitting within 15 the screw threads of the portion 28. The limit switch 81 is so located as to be actuated by the pin 84 to prevent further turning of the lowermost switch, thereby ensuring that, when the motor operation is reversed, the 20 lowermost switch is immediately ready for operation in the reverse direction.

If the motor 46 is energized to cause a turning movement of the switches in a clockwise direction, the lowermost switch 47b is actuated first and in its upward movement the top of the bar 48b engages the end of the lug 66 of the bar 48a and effects disengagement of the lug 65 on the bar 48a from the resilient holding means. At the same time the lug 61 25 on the bar 48a engages the screw threads of the portion 27 whereby a further continuous turning movement of the switch 47a is effected. The top of the bar 47a engages the lug 66 in the bar 48 and the same sequence 30 of operations is effected as was hereinbefore described for the bar 48b and the lug 66 on the bar 48a. The relative location and dimensions of the cooperating parts effective in the serial actuation of the switches is such 35 that all of the circuits connected to one switch are energized or de-energized before the circuits connected to the next switch are energized or de-energized whereby a plurality of circuits may be energized or de-energized 40 in a predetermined sequence.

In Fig. 4 of the drawings I have illustrated a plurality of light sources 151, 152, 153, and 154 that are electrically connected to an elongated tube 47 to be controlled thereby by a 45 turning movement thereof. I have illustrated successive levels of an upper surface of the fluid connector 57, when the tube 47 is given a turning movement in a counter clockwise direction, by the broken lines indicated by the numerals 155, 156, 157, 158 and 159 respectively.

A supply circuit conductor 161 is connected to the first contact terminal 52, while the contact terminals 53, 54, 55 and 56 are connected 50 to one terminal of the respective light sources. The other supply circuit conductor 162 is connected to the other side of the respective light sources hereinbefore mentioned.

When the tube 47 is tilted farthest upwardly the fluid has the position indicated

by the line 155 and hence none of the light sources are energized. When the tube 47 has been given a predetermined movement in a counter clockwise direction, the mercury level is indicated by the line 156. This establishes a connection between the contact terminal 52 and 53 and therefore energizes the light source 151. A further turning movement brings the mercury level to the line 157 and thereby energizes in addition 75 the light sources 152. Further turning movement brings the mercury to the line 158, thereby energizing the light sources 153, and in the final position the fluid level is indicated by the line 159 energizing the light sources 154 in addition to all the others.

In Fig. 5 of the drawings I have illustrated the use of an elongated tube switch in controlling the energization of a single light source through a resistor 163 that is provided with four spaced leads that are connected to the respective contact terminals 53, 54, 55, and 56 of the fluid connector switch. The contact terminal 56 is connected to one end of the resistor 163 and also to one terminal of a light source 164, the other terminal of which is connected to a supply circuit conductor 162. When the fluid level is indicated by the line 155 the light source 154 is fully de-energized. When the fluid level is indicated by the line 156 all of the resistance of the resistor 163 is connected in circuit with the light source 164. Further turning movement of the tube 47 so that the fluid level is indicated by the lines 157, 158, and 159 successively, cuts out one portion after the other of the resistor 163, thereby increasing the current traversing the light source 164 and increasing the intensity of the light produced thereby. This allows of a greater load being carried by a switch, since the amount of the sudden rush of current makes a great difference in the carrying capacity of such a switch. It may be noted that in the above described operation, the fluid connector switch varies the energy expended in an energy-translating device, in a plurality of steps or by successive steps.

In my copending application Serial No. 684,162, filed Jan. 3, 1924, I have disclosed a system of light and color play and have indicated that it is possible to add entire light units to others already energized, while still increasing the intensity of illumination by steps of least visible increments. A rheostat for controlling the energization of a light source by steps of least visible increments is disclosed and claimed in my Patent No. 1,357,773. The steps of the resistor 163 in the diagram of connections illustrated in Fig. 5 of the drawings are so selected, relatively to the light source 164, that the intensity of illumination is increased by steps of least visible increments as the consecutive portions of the resistor 163 are short circuited by the

continued turning movement of the tube 47. The tube 47 illustrated in Fig. 5 of the drawings may therefore represent the uppermost tube of the switch mechanism illustrated in Fig. 1 of the drawings, that is being employed in controlling the illumination of an auditorium, the intensity being varied by steps of least visible increments.

The diagram of connections illustrated in Fig. 4 of the drawings may also represent a system in which the intensity of illumination is increased by steps of least visible increments by the successive additions of either an entire light unit or of a plurality thereof. In other words the respective light sources 151, 152, 153, and 154 are so selected as to their respective intensities that the illumination provided thereby will be by steps of least visible increments. These least visible increments of illumination may be computed to be effective simultaneously in various sections of the auditorium, to make a reduction or an increase of illumination universal, when such plan is desired. This may include stage, auditorium proper and street front as desired.

If the motor 46 is constructed as a direct current shunt wound motor it may be so energized as to operate at any predetermined speed, and its operation, effected by the means illustrated in Fig. 6 of the drawings, is under the direct volitional control of an operator. As the operator presses downwardly on the member 94 he increases the speed of the motor, that is the greater the pressure by the operator's hand, the greater the speed of the motor. In addition, the longer the motor is permitted to operate, the greater will be the turning movement of the actuating shaft driven thereby and hence the greater will be the amount of turning movement of the successive plural contact fluid connector switches actuated by the actuating shaft.

It may be desirable at times to move the plurality of switches to predetermined positions such, for instance, as illustrated in Fig. 1 of the drawings, before the main line control switch is closed. In such cases it is highly desirable to know how many light units will be energized or what the intensity of illumination will be when the main line switch is closed, and the indicator on the disk 76 will give such information when the scale 77 is calibrated in light units or in intensity of illumination. The operator need only continue the energization of the driving motor until such time as the pointer 78 is opposite the proper number of light units on the scale 77 when he will effect de-energization of the motor and then effect the closing of the main line circuit breaker.

I have illustrated such a system in Fig. 7 of the drawings wherein supply circuit conductors 165, 166, and 167 comprise a three-

wire system of supply of electric energy. A main line circuit breaker 168 controls the energization of all of a plurality of light sources while a remote controlled circuit breaker 169 controls the energization of that part of the light sources arranged as to give a blue light only. A second remote controlled circuit breaker 171 controls the energization of another portion of the light units that are adapted to give a red light only. A third remote controlled circuit breaker 172 controls light sources giving a white light only, while a fourth remote controlled breaker 173 controls light sources giving amber light only or any other desired spectral color, it being understood that varying quantities of light are needed for the varying colors, since these are not found in equal proportions in artificial light. As noted above, the circuit breakers 168, 169, 171, 172, and 173 may all be remote controlled by an operator from a light console of the type disclosed and claimed in my co-pending application, Serial No. 684,162 filed Jan. 3, 1924, while the circuit breakers themselves may be located at any suitable or desired point with reference to the plurality of light units which may be distributed in more or less uniform manner around an auditorium. I have illustrated a panel board 174 with a plurality of fuses 175 and 176 for each of the subdivisions of the groups of light units and plural contact fluid connector switches such as hereinbefore described may be connected in circuit with the respective circuit breakers 169, 171, 172 and 173 in order to control the energization of the respective groups of lamps, or the fluid connector switches may be connected in circuit with the respective subdivisions of light units one of which is indicated by the numerical 177.

If it is desired to bring up the illumination of one of the groups of lamps, for instance that controlled by the circuit breaker 169, the operator need only cause the closing of the main breaker 168 and then of the breaker 169, after which he may energize the motor 46 and operate the same at any desired speed to effect an increase in the intensity of illumination in any desired timed sequence. He may stop the increase of illumination at any desired point by de-energizing the motor, and may reduce the intensity by reversing the operation of the motor.

It may become desirable to effect automatic control of the speed of the actuating motor and Fig. 9 of the drawings illustrates schematically a means for expecting such control. The upper end of the shaft 21 illustrated in Fig. 1 of the drawings has an extension 178 thereon, that carries a worm 179. A worm wheel 181 is engaged and actuated thereby and is mounted on a suitable shaft 182 which carries a pinion 183. A cam member 184 has its upper surface formed as a

rack bar with teeth 185 that are in engagement with the pinion 183. The lower surface of the bar 184 is provided with a cam surface 186 of a predetermined shape. The 5 cam member 184 moves in a supporting member 187, that may be of channel form in lateral section and have a longitudinally extending slot 188 in the bottom portion thereof.

A two part lever 189 is pivotally mounted 10 on the member 187 and has its outer end operatively engaging the motor speed controlling rheostat 95 illustrated in Fig. 6 of the drawings. An arm 191 extends from the 15 lever 189 and carries a roller 192 that operatively engages the cam surface 186. A spring 193 ensures that the roller 192 will be pressed against and follow the cam surface and vary the position of the lever 189 relatively to the resistance 95 to vary the speed 20 of the motor 46.

The above described automatic control mechanism may be mounted on the top of the skeleton frame illustrated in Fig. 1, or in any other suitable or convenient location. 25 As stated above the illustrated arrangement is schematic only and any equivalent mechanism effective for the purpose described may be employed.

It is evident that any desired time sequence 30 of motor operation may be effected by providing a suitable cam surface and provides an automatic counterpart of any predetermined choice of light succession for any purpose, whether conceived as a fine art or for the 35 purposes of convenient utility, such as timing the number of seconds or minutes required for lowering or raising the lighting of a stage or auditorium.

Each cam surface would have its particular 40 form or pattern in accordance with its use or the feeling it is meant to counterpart, previously determined on through the volitional choice of the operator. The controlling mechanism with or without the automatic element, may be made a part of any light player 45 console.

Should the operator desire to fully energize a predetermined number of light units, he may do so by effecting operation of the 50 motor for a predetermined length of time until the indicator associated therewith shows that the fluid connector switches have been moved to such a point as will permit energization of the desired number of light sources when the main circuit breaker is closed. Upon closing either the main circuit breaker or the secondary circuit breaker, the desired number of light sources will be 55 fully energized.

It will be remembered that I have suggested 60 the use of a plurality of supporting frames and of fluid connector switches, and I may employ such a mechanism in connection with the four groups of lamps illustrated in Fig. 7 of the drawings. That is,

one of the fluid connector switches may be connected in circuit with one of the subdivisions of the group of lamps controlled by the breaker 169, a second fluid connector switch connected in circuit with one of the 75 subdivisions of the group of lamps controlled by the breaker 171, and so on for the other two groups of lamps. As there are three or a multiple of three subdivisions in each group, illustrated in Fig. 7 of the drawings, the three successively actuated fluid connector switches may be connected to control the energization of different subdivisions of the respective groups of light units. Hence, any desired color of illumination may be obtained by the operator by controlling the operation of the respective breakers 169, 171, 172, and 173. As hereinbefore noted, a switch mechanism comprising respective pluralities of fluid connector switches as illustrated in Fig. 8 of the drawings, where however, only two such switches are illustrated.

Referring more particularly to the modification illustrated in Figs. 10 and 11 of the drawings, the operation thereof is substantially as follows:— It is understood that the operation of the motor 128 was terminated with the teeth of the pinion 132 still in mesh with the teeth of the gear wheel 119. The limit switch 139 prevents the operation of the motor in such direction as to cause a turning movement of the gear wheel 119 in a clockwise direction as viewed from the right hand end of the shaft 107. The spaced 100 terminal members 112 of the tube 108 are in substantially the position shown by the broken lines in Fig. 10 of the drawings, that is, they are disengaged from the connecting fluid 113 in the tube. Upon energization of the motor 128 the pinion 132 causes a turning movement of the gear wheel 119 and of the tube 108 in a counter clockwise direction, and the left hand terminal member 112 first operatively engages the connecting fluid 113. If this is connected to one supply circuit conductor, a circuit is established as soon as the second contact terminal 105 operatively engages the connecting fluid. It is evident that the connecting fluid remains in substantially the same position while the annular tube is undergoing a turning movement on the shaft 107 by the gear wheel 119.

As the pinion 132 continues its turning movement and effects a corresponding turning movement of the gear wheel 119, one contact terminal after another is moved into engagement with the connecting fluid 113, thereby energizing the light sources electrically connected thereto. When the turning movement of the gear wheel 119 has continued to such a degree that the pin 144 operatively engages the member 145, the gear wheel 121 is given a turning movement until the teeth thereon operatively mesh with the 115 120 125 130 135 140 145 150 155 160 165 170 175 180 185 190 195 200 205 210 215 220 225 230 235 240 245 250 255 260 265 270 275 280 285 290 295 300 305 310 315 10045 10050 10055 1

teeth of the pinion 133. At about this time the gear wheel 119 has been moved to such a position that the last tooth thereof is out of engagement with the pinion 132, after which no further turning movement of the gear wheel 119 can take place, and the latter is held in its normal operative position by the engagement of the pin 144 with the resilient holding member 148. In this position all of the spaced terminal members 112 are in engagement with the connecting fluid in the tube 108.

Further turning movement of the shaft 123 causes a corresponding turning movement of the gear wheel 121, and a successive energization of light sources connected to the respective terminal members extending into the tube 109. When the member 146 engages the member 147 the gear wheel 122 is given a turning movement that effects the meshing thereof with the pinion 134. The gear wheel 122 is then permitted to remain in its normal operative position with the member 146 engaging the resilient member 149, further turning movement thereof being prevented by the lack of further teeth in the gear wheel 121.

The operation of the motor 128 may continue until the member 143 engages the limit switch 142, which effects de-energization of the motor, with the teeth of the pinion 134 and of the gear wheel 132 still in mesh, and with all of the annular switch tubes moved to their fully energized positions. As was hereinbefore stated in connection with the device illustrated in Fig. 1 of the drawings, when the mechanism has been moved to one of its limiting positions the motor can be energized only to run in the opposite direction, and hence if all of the switches are in their fully energized position they may be moved only to a position that de-energizes one or more of the light sources controlled thereby.

When the motor 128 is energized to run in the opposite direction to effect a turning movement of the switch tubes serially in clockwise direction as viewed from the right hand end of the shaft 107, the action of the various parts of the device is substantially similar but in a reverse sense. The pin 147 operatively engages the pin 146 which has been in engagement with the resilient holding member 149 and moves it and the gear wheel and annular tube in a clockwise direction until the teeth on the gear wheel 121 engage the teeth on the pinion 133, after which further turning movement of the gear wheel 121 and of the switch 109 associated therewith is effected by the pinion 133. The pin 147 is held by the member 149 whereby the switch 111 is held in its normal inoperative position. The annular switch tubes are thus operated serially or successively until the tube 108 has been moved into its normal inoperative position when further turning

movement is stopped by the de-energization of the motor 128 by reason of the actuation of the limit switch 139 by the pin 141. It is understood that the diagram of connections illustrated in Fig. 6 is employed with this form of device and that the mechanism illustrated in Fig. 9 is also applicable to it, such modifications being made as are necessary to adapt it to be operatively associated therewith.

The device embodying my invention thus provides a relatively simple and compact means for controlling the energization of a plurality of light sources, said means comprising a plurality of plural contact, fluid connector switches that are successively or serially actuated by a motor that is under the volitional, manual control of an operator to effect any desired timed sequence of operation of the successive switches.

The device embodying my invention provides relatively simple means operatively associated with the actuating means for limiting the travel thereof in either direction of operation, and I further provide means for indicating the number of light sources energized at any time or for indicating the intensity of illumination corresponding to any predetermined position of the mechanism.

The device embodying my invention further provides a means for effecting automatically and predetermined sequence or progress of the energization or de-energization of a plurality of circuits or light sources, which means is actuated by the mechanism itself.

Such a timed sequence of illumination control may be used as a means of abstract and emotional expression. In this event the exercise of such choice as to make clear the purpose of any illumination succession, will require time, thought and labor, and once determined on and embodied in a cam surface can be easily made available to many through such automatic mechanical patterns as have been used in the phonograph, or the automatic piano for multiplying a conception once made. The cam pattern herein disclosed permits of effecting repeated operations of the switch mechanism also herein disclosed, according to a light-color sequence once determined upon as being the most fitting to accompany a parallel expression made simultaneously in another art, or for its own sake.

Various modifications may be made in the device embodying my invention without departing from the spirit and scope thereof, and I desire that only such limitations shall be placed thereon as are imposed by the prior art.

I claim as my invention:

1. A switch mechanism comprising a plurality of switches, power actuated means for effecting actuation of the switches, means whereby actuation of one switch initiates ac-

tuation of a succeeding switch, and means for controlling in a predetermined manner the timing of the successive actuations, said last named means including a controlling pattern member.

2. A switch mechanism comprising a plurality of switches, power actuated means for effecting actuation of the switches, means whereby actuation of one switch initiates actuation of a succeeding switch, and means for controlling in a predetermined manner the timing of the successive actuations, said last named means including a controlling pattern member determining the speed of operation of the power actuated means.

3. An electric current controlling mechanism, comprising a plurality of current connecting units, current modifying means associated with one or more of said units, power actuated means for effecting actuation of said units, means whereby actuation of one unit defines actuation of a succeeding unit and means for controlling in a pre-determined manner the successive actuations, said last named means including a controlling pattern member.

In testimony of which invention I have hereunto set my hand, at Philadelphia, Pennsylvania, on this sixth day of January, 1927.

30 MARY HALLOCK GREENEALT.
